UNITED STATES PATENT OFFICE

1,998,043

TIE-PLATE

James K. Boyd, Wilkinsburg, and Frank F. Slick,
North Braddock, Pa.

Application March 17, 1932, Serial No. 599,566

7 Claims. (Cl. 238—304)

This invention relates to railway tie-plates, one of the objects being to hold the rails down in a resilient manner so that when they are flexed by the passage of a train they will not become loosened from the ties. Other objects will be understood from the following disclosure.

Having reference to the accompanying drawings which illustrate various specific forms of the invention:

- 10 Figure 1 is a side elevation.
- Figure 2 is a top plan.
- Figure 3 is a cross-section from the line III—III in the first figure.
- Figure 4 is a side elevation of a modification.
- 15 Figure 5 is a cross-section from the line V—V in Figure 4.
- Figure 6 is another modification.
- Figure 7 is a cross-section from the line VII—VII in Figure 6.
- 20 Figure 8 is a further modification.
- Figure 9 is a top plan of a detail of Figure 8.
- The invention primarily consists of a base-plate 1 having a pair of upstanding apertured lugs 2 arranged to straddle the base of a rail 3.
- 25 This base-plate is preferably made from a rolled section of metal so that when in its final form the fibrous structure of the metal is at right angles to rail-holding stresses. In practice this means that the fibrous structure will be at right angles to the rail. The surface of the base-plate 1 between the upstanding lugs deviates from the horizontal sufficiently to give the rail its proper cant, this naturally varying to meet different conditions.
- 30 Spring steel apertured clips 4 are fitted over the upstanding lugs 2 and contact the base of the rail 3 and the top of the plate 1. Wedges 5 are then driven through the apertures in the lugs 2 so as to flex the clips 4 downwardly, the latter then resiliently holding the rail 3 down. The plate 1 is, of course, spiked to a rail.

The wedges 5 are each formed with a pair of projections 6, one of which is higher than the other. When inserted in the apertures of the lugs 2 one of these projections will drop in the apertures in the clips 4, locking the wedge in place, and the opposite wedge will press against the top of the aperture in the lug, and by inserting the wedge in different positions the tension exerted by the clips 4 may be varied.

Instead of the wedges 5 pins 7 may be used. These pins have flat sided ends and central eccentric cylindrically sided bodies 8 which have flat sides 9. By turning one of these flat sides towards the clips one of these pins may be shoved

into the aperture of one of the lugs without the necessity of first flexing the clips. A wrench may then be applied to the flat sided ends to rotate the pin so that one or the other of its cylindrical sides is forced into the apertures in the clips, the other side pushing against the top of the lug and applying tension to the rail through these clips. This tension may be varied because of the eccentricity of the central body 8.

The locking means which have been described up to the present provide only two degrees of tension. If more than that is desired it may easily be provided for. One example consists of a cam-shaped member 10 having a wrench 15 operable end 11 and a stub-shaft 12. A second member exactly similar to this, with the exception of the stub-shaft, is bored so that it can be slipped over the latter. Each part has a slightly projecting ring 13 on its inner edge. This form is used by slipping the stub-shaft 12 through the aperture in the lug 2 and placing the bored member over it, the ring portions 13 of each having a flattened part which permits this operation without depression of the clips 4. A wrench may then be applied to the two members to rotate them so that the ring portion drops into the aperture in the top clips and the cam surfaces 10 depress the same. Further rotation will vary the tension applied to the base of the rail. The 30 degrees of variation possible are only limited by the number of the cam surfaces 10.

The spring clips 4 have been shown fitted over the lugs 2 in pairs in each instance. This is preferable because of the greater degree of flexibility provided. However, a single heavier spring clip might be used. If it is desired to hold the rail solidly, rigid steel clips 14 may be used, their parts which contact the pins being slightly upwardly bowed to springingly hold the retaining pins in place.

Although specific forms of this invention have been shown and described in accordance with the patent statutes, it is not intended to limit their scope exactly thereto, except as defined by the 45 following claims.

We claim:

1. A railway tie-plate assembly including a base-plate having an upstanding apertured lug, a clip apertured to fit over said lug and constructed to contact said base-plate and the base of said rail, and means having a plurality of different surfaces arranged radially about and different distances from a common center line for insertion through said apertured lug in rotatively

- different positions to hold down said clip with relatively different forces.
2. A railway tie-plate assembly including a base-plate having upstanding apertured lugs arranged to straddle the base of a rail, spring steel clips apertured for plural fitting application over said lugs and constructed so that in each instance the lowermost clip bridges between the base of said rail and said base-plate and means that can be inserted through said apertured lugs to flex said clips downwardly.
3. A railway tie-plate assembly including a base-plate having upstanding apertured lugs arranged to straddle the base of a rail, spring steel clips apertured for plural fitting application over said lugs and constructed so that in each instance the lowermost clip bridges between the base of said rail and said base-plate and adjustable means that can be inserted through said apertured lugs to flex said clips downwardly varying distances.
4. A railway tie-plate assembly including a base-plate having upstanding apertured lugs arranged to straddle the base of a rail, clips apertured to fit over said lugs and constructed to contact said base-plate and the base of said rail, and wedges having differently sized opposed projections on their sides and constructed for insertion through said apertured lugs with one or another of these projections extending down in the apertures in said clips.
5. A railway tie-plate assembly including a base-plate having upstanding apertured lugs arranged to straddle the base of a rail, clips apertured to fit over said lugs and constructed to contact said base-plate and the base of said rail, and pins having flat sided ends with central eccentric cylindrically sided bodies which are flattened at points permitting free insertion in said apertured lugs.
6. A railway tie-plate assembly including a base-plate having upstanding apertured lugs arranged to straddle the base of a rail, clips apertured to fit over said lugs and constructed to contact said base-plate and the base of said rail, and cam faced concentrically ringed members having wrench operable ends and stub-shafts and other cam surfaced concentrically ringed members constructed to fit said stub-shafts when inserted through said apertured lugs, each of these member's ringed parts having a flattened portion permitting its free passage over the apertures in said clips.
7. A railway tie-plate assembly including a base-plate having at least one upstanding apertured lug arranged adjacent the base of a rail, at least one clip apertured to fit over said lug and constructed to contact said base-plate and the base of said rail, at least one cam-faced member and means insertable through said lug for holding said member with the cam surfaces thereof of pressing against said clip or clips.

JAMES K. BOYD.
FRANK F. SLICK.
